UNITED STATES PATENT OFFICE.

FRANK M. BURROWES, OF PORTLAND, MAINE.

TOY BUILDING-BLOCKS.

1,009,468.

Specification of Letters Patent. Patented Nov. 21, 1911.

Application filed August 15, 1910. Serial No. 577,356.

To all whom it may concern:

Be it known that I, FRANK M. BURROWES, a citizen of the United States, and a resident of Portland, in the county of Cumberland and State of Maine, have invented a new and useful Improvement in Toy Building-Blocks, of which the following is a specification.

My invention relates to toy building blocks for building toy houses and other like constructions. Hitherto such building blocks have been commonly made so that they will rest, one upon another without any fastening, the whole being held together simply by the weight of the blocks.

The object of my invention is to construct a set of building blocks whereby a child may put together a house or any similar construction in such a way that it will hold together firmly and may be used for the purpose of a play house or in the manner of a permanent toy.

A further object is to render toy constructions easy to build by making the blocks stick firmly together as the building goes on as distinguished from resting one block on another a process which requires a very steady hand.

The invention consists of the several features of construction as hereinafter described and claimed.

I have illustrated my invention by means of the accompanying drawings in which—

Figure 1 is an end elevation of a toy house constructed of my improved building blocks, Fig. 2 is an end view of two courses of the roof blocks, Fig. 3 is a face view of the same, Fig. 4 is an end view of two of the common blocks fitted together, Fig. 5 is a face view of the same, Fig. 6 is a perspective view of one of the common blocks, Fig. 7 is an elevation of a modified form of the common blocks showing the manner of forming a pier or column, Fig. 8 is a side elevation of one of the wedge-shaped blocks for completing the roof courses and for other purposes, Fig. 9 is an end view of the same, Fig. 10 is an end view of the two ridge pole pieces and Fig. 11 is a detailed section on the line $\alpha\alpha$ of Fig. 1.

The set of blocks as I prefer to make them up consist of the common oblong blocks A shaped approximately like an ordinary brick and capable of being laid up, course

upon course, like brick work. Each block 55 is secured to the block below it by a groove c' formed on its under side and adapted to fit a corresponding tongue or rib a in the next block below. These tongues and grooves are made central and longitudinal of the 60 blocks for ordinary straight work but for building up columns and piers and the like and for turning corners, certain blocks are formed with one transverse groove as shown in Fig. 7 or with two as shown in Fig. 65

Door frames and window frames are provided and may be fitted in place and the blocks are joined to the casings of the window and door frames by ribs and grooves as shown in Fig. 11 where a rib b is formed 70 on the casing of the window frame B which fits a groove in the end of the block.

In forming the corners of the building, blocks are selected which have one transverse groove as well as the longitudinal 75 groove as shown in Fig. 1.

The slope of the roof is formed by the roof courses which are terminated by wedge-shaped blocks F having grooves on their under sides and when fitted in the ends of 80 the roof courses they form a true roof slope. The roof is made up of flat roof blocks as C made in full and half lengths. Each block has a dovetail groove c' on its lower edge and a corresponding rib on its upper edge. 85 As I prefer to make this joint, the rib consists of a cylindrical bead slightly offset with a groove which enables the rib to be inserted when the parts are held at an angle. When the blocks are laid down flat they will 90 not pull apart. A roof covering may thus be built up by securing the several courses together at the edges and having the blocks of each course break joints, which will hold together and form a substantially solid 95 piece.

To secure the covering pieces in place on the slope of the roof, I provide ridgepole pieces which have grooves in one edge to fit the ribs of the regular roof blocks, the upper or adjacent edges being tongued and grooved so that they may be readily secured together.

As already pointed out, certain blocks have two transverse grooves on the bottom for building up columns as shown in Fig. 7. 105

All the parts used have this characteristic, that they are fastened together by ribs and grooves fitting together.

A set of blocks made in this way may be used to build a great variety of constructions and each one after being built will be to a great extent permanent. It may be used for a play house and rebuilt in other forms enabling children to exercise their skill and inventiveness to any extent.

The sets of blocks may be made with any desired number in a set and with sufficient 10 number of blocks large and elaborate toy buildings may be built.

I claim:

1. A set of building blocks including 15 cooperating members having interfitting tongue and grooved portions formed to register and engage edgewise in one position of said members and prevent separation in another position thereof.

2. A set of building blocks including 20 operating members having complementary connecting instrumentalities formed to register and engage edgewise in a predetermined relation of said members and to interlock to prevent separation in another relation 25 thereof.

3. A set of building blocks including 30 cooperating members having tongue and grooved portions arranged in one position to permit edgewise entrance of the tongue into the groove and in another position to cause the tongue to hook in the groove and prevent separation of the members.

4. A set of building blocks including 35 cooperating members having a tongue and groove preventing separation of the members when in a common plane and permitting separation thereof upon angular disposition of said members.

5. A set of building blocks including 40 cooperating members having a tongue and groove adapted to be engaged when the members are in a predetermined relation and to interlock to prevent disengagement

and to form an angle or ridge upon changing the relation of said members.

45

6. A set of building blocks including a pair of ridge pole pieces, each of which is formed on its lower edge to engage roof blocks, said ridge pole pieces having a detachable engagement therebetween at their 50 upper edges, substantially as described.

7. A set of building blocks including a pair of ridge pole pieces, each of which is formed on its lower edge to engage roof blocks, said ridge pole pieces having a detachable engagement therebetween at their 55 upper edges comprising interlocking tongue and groove portions, substantially as described.

8. A set of building blocks including flat 60 rectangular roof blocks, each having a dovetail groove on one edge, one side of said groove being offset inside of the mouth or opening of the groove, and a corresponding tongue on the other edge of each block 65 adapted to enter said groove when the blocks are at an angle and to permit the blocks being brought to a common plane.

9. A set of building blocks including flat 70 rectangular blocks made in whole and half lengths, each block having a groove on one edge and a corresponding tongue on the other edge, a pair of flat ridge pole pieces each of which has a groove on its lower edge 75 to fit the tongues of the roof blocks, and one of which has a lateral groove near its upper edge, the other having a tongue on its upper edge to fit said lateral groove.

Signed at Portland in the county of 80 Cumberland and State of Maine, this thirteenth day of July, 1910.

FRANK M. BURROWES.

In the presence of—

S. W. BATES,

PERCY M. ANDREWS.
